PULP MOLDING DIE

Ernest L. Shepard, Fairfield, Maine, assignor, by
mesne assignments, to The Canal National
Bank of Portland and William B. Nulty, Port-
land, Maine, as trustees

Application May 19, 1949, Serial No. 94,180

7 Claims. (Cl. 92—54)

1

This invention relates to an open-face pulp molding die-unit for the suction formation, from a pulp-water slurry, of molded pulp articles such as egg flats or analogous articles.

This application is a continuation-in-part of my application S. N. 402,478 filed July 15, 1941, now abandoned, and my application S. N. 571,753 filed January 8, 1945, also abandoned.

In the present invention I have provided a pulp molding die-unit embodying a unitary die-plate, the molding area of which is defined by a die-ring. A plurality of grooves which open out into the molding area divide it into a plurality of border sub-areas located adjacent to the die-ring and, in addition, a plurality of inner sub-areas disposed inwardly of the border sub-areas. Each sub-area, or minor molding area, has a conformation corresponding to the section of the article to be molded thereon. A plurality of wire mesh screen hoods each snugly engages the die-plate and a sub-area thereof. Each hood associated with the inner sub-areas has marginal flanges which extend into the contiguous grooves defining the perimeter of the inner sub-area, and each hood is frictionally locked within its respective perimetric groove. Each hood of the border sub-areas has marginal flanges, including flanges which are directly adjacent to the die-ring. Such adjacent flanges are frictionally locked to the die-plate, and the non-adjacent flanges of such hoods extend into contiguous grooves and are frictionally locked therein. By this construction at least those hoods which are associated with the inner sub-areas may be initially positioned or replaced from the face side of the unitary die-plate, and are held in place independently of the die-ring.

According to one specific embodiment of the invention, the hood flanges directly adjacent to the die-ring extend between the die-ring and the die-plate, and are frictionally locked therebetween. With such construction, each of the hoods associated with the inner sub-areas may be initially positioned or replaced from the face side of the unitary die-plate, and are held in place independently of the die-ring.

According to another embodiment of the invention, the die-plate is provided with a perimetric groove at the margin of the molding area just inside the inner wall of the die-ring, and the hood flanges directly adjacent to the die-ring extend downwardly into said perimetric groove and are frictionally locked therein. With this construction, all of the individual hoods over the entire molding area of the die-plate may

2

be initially positioned or replaced from the face side of the unitary die-plate, and are held in place independently of the die-ring.

In the drawings:

Fig. 1 is a plan view of an open-face pulp molding die-unit showing grooves extending substantially to the die ring, and showing certain of the wire mesh screen hoods in position;

Fig. 2 is a vertical section on line 2—2 of Fig. 1;

Fig. 3 is a fragmentary vertical section taken on line 3—3 of Fig. 1 showing certain screen hoods in position with depending flanges disposed in grooves in the die-plate and with an outwardly extending flange frictionally held between the die-plate and the die-ring;

Fig. 4 is a fragmentary vertical section taken on line 4—4 of Fig. 1;

Fig. 5 is a fragmentary plan view of a die-unit showing a modified form of groove construction wherein the grooves extend substantially to the die-ring but wherein portions of the grooves extend under the die-ring;

Fig. 6 is a fragmentary vertical section taken on line 6—6 of Fig. 5 showing screen hoods with depending and outwardly extending flanges;

Fig. 7 is a fragmentary plan view of a die unit showing another form of construction wherein grooves in the die plate extend substantially to the die ring and intersect a perimetric groove disposed just inside the inner wall of the die-ring;

Fig. 8 is a fragmentary vertical section on line 8—8 of Fig. 7;

Fig. 9 is a fragmentary sectional view showing a modification of the invention wherein the perimetric groove is formed in part by the inner wall of the die-ring;

Fig. 10 is a perspective view of a contoured screen hood with a plurality of depending flanges and with an outwardly extending flange;

Fig. 11 is a perspective view of a contoured screen hood wherein all of the flanges extend downwardly;

Fig. 12 is an enlarged fragmentary sectional view of a portion of a die-plate showing depending flanges of a screen hood frictionally locked within grooves by means of locking keys;

Fig. 13 is a still further enlarged fragmentary vertical section showing depending flanges of screen hoods frictionally locked in a groove by means of a locking strip; and,

Fig. 14 is a fragmentary vertical section similar to Fig. 13 showing depending flanges of screen hoods frictionally held in position without additional locking means.

In Figs. 1 to 4 inclusive I have disclosed an embodiment of my invention in which the intersecting grooves extend substantially to the die-ring and wherein the screen hood flanges adjacent to the die-ring extend thereunder and are frictionally held between the die-ring and the die-plate. In this embodiment there is shown a one piece or unitary die-plate 2 (Fig. 2) to which is secured by suitable means such as screws 4, a die-ring 6. The inner wall 8 of the die-ring defines the molding area 10 and the edge of the article to be molded thereon. The molding area 10 is substantially parallelogrammatic, and specifically rectangular, in shape. Surrounding the molding area 10 on the die-plate 2 is the peripheral portion 12 and to this peripheral portion 12 the die-ring 6 is shown as secured. Over its entire molding area 10 the die-plate 2 is provided with drainage openings 14 leading therethrough from said molding area 10. These drainage openings 14 are shown in Fig. 2, are shown in part in Fig. 1, and for simplification are omitted from Figs. 3 and 4.

The unitary die-plate 2 is shown as provided with a set of grooves 16 which as shown do not extend all the way through the thickness thereof but which do open out through the molding area 10 of the die-plate. These grooves are shown as spaced apart and substantially parallel with one another and with one pair of inner walls 8a (Fig. 1) of the die-ring 6. The grooves 16 are shown as extending substantially to the inner walls 8b of the die-ring 6.

The die-plate 2 is further provided with a similar and second set of grooves 18 opening out through the molding area 10 of the die-plate. The grooves 18 are spaced apart and are substantially parallel with each other and with the inner walls 8b of the die-ring 6. The grooves 18 of the second set extend substantially to the inner walls 8a of the die-ring. The grooves 18 cross the grooves 16 of the first set at substantially right angles to form a plurality of minor molding areas or sub-areas. Thus there are formed the minor molding areas 20, 22 and 24.

The minor molding areas or border sub-areas 20 (Fig. 1) are contiguous to the inner wall 8 of the die-ring 6 on two sides and the minor molding areas 22 are contiguous to the die-ring wall 8 on one side. Together, the minor molding areas 20 and 22 constitute a plurality of border sub-areas located contiguous to the die-ring 6, and each of said border molding areas 20 and 22 has at least one side directly adjacent to the inner wall of the die-ring 6. The minor molding areas 24 constitute a plurality of inner sub-areas disposed inwardly of the border sub-areas and each of the inner sub-areas 24 is bounded on all sides by contiguous portions of grooves 16 and 18.

Each of the minor molding areas 20, 22 and 24 has a conformation corresponding to the section of the article to be molded thereon and to this end may be provided with individual forming projections 26 (Fig. 2) and pocket forming cavities 28.

There is provided a fine wire mesh hood individual to each sub-molding area 20, 22 and 24 and providing the forming surface thereof. Thus a hood 30 is provided for each molding area 20, a hood 32 is provided for each molding area 22 and a hood 34 is provided for each molding area 24. The total of these hoods 30, 32 and 34 constitute a screen snugly engaging the die-plate 2 over the molding area 10 thereof and each hood constitutes the foraminous cover for a minor molding area. Each hood 30, 32 and 34 is parallelogrammatic, and specifically rectangular, in shape.

The hoods 30 have the outwardly extending flanges or marginal portions 36 which extend beneath the contiguous portion of the die-ring 6 and which are shown as frictionally held between the die-ring 6 and the peripheral area 12 of the die-plate 2 by being removably clamped between said die-ring and said peripheral area of the die-plate. The hood 30 has additional depending flanges 38 which extend into grooves 16 and 18 and are frictionally retained therein.

Each of the hoods 32 (Figs. 1, 2 and 10) has an outwardly extending flange or marginal portion 40 extending beneath the contiguous portion of the die-ring 6 and arranged to be removably clamped between said die-ring and the peripheral area 12 of the die-plate, whereby said flange 40 may be frictionally held therebetween. The hood 32 has additional and depending marginal flanges 42 which extend into and are frictionally held within, the contiguous portions of the grooves 16 and 18 which define the border sub-areas with which the hood is associated.

The hoods 34 (Figs. 1, 3 and 11) associated with the inner sub-areas 14 have depending flanges 44 at their marginal edges which extend into grooves 16 and 18 and are retained solely by friction in those portions of the grooves 16 and 18 which define the sub-area with which the hood is associated. In other words, each hood 34 is frictionally locked within its respective minor perimetric groove constituted by the contiguous portions of the grooves 16 and 18.

While the depending flanges of the hoods 30, 32 and 34 may be frictionally locked within the contiguous portions of the grooves 16 and 18 in any suitable manner, it is convenient and preferred to accomplish this frictional retention by means of locking strips 46 as indicated in Figs. 2, 3 and 4.

From the construction herein above described, it will be noted that any of the hoods 34 associated with the inner sub-areas 24 may be removed from the front of the die and replacement hoods substituted, without disturbing the die-ring or removing any of the other hoods associated with either the inner areas 24 or the border sub-areas 20 or 22.

The unitary die-plate 2 may be associated with a die carrier 41 (Fig. 2) of a pulp molding machine by suitable fastening means such as screws 43 to provide the drainage chamber 45 which may be connected by a pipe or conduit 47 with suitable means for producing suction during the forming operation, and alternatively pressure, if desired, in assisting to displace a formed article from the molding area.

In Figs. 5 and 6 I have illustrated a modification of the die construction shown in Figs. 1 to 4 inclusive, wherein the grooves extend substantially to the die-ring but wherein portions of such grooves extend under the die-ring. The unitary die-plate 48 has a peripheral area 50 to which is attached the die-ring 52 by suitable means such as the screws 54. The inner wall 56 of the die-ring 54 defines the molding area and the edge of the article to be molded. The die-plate 48 is provided with drainage openings 58 leading therethrough from the molding area. The molding area is divided into minor molding areas 60 by a set of grooves 62 which are spaced parallel to each other and to the inner walls 56a of the die-ring, and by the grooves 64 which are also spaced parallel to each other and to the inner wall 56a of the die-ring and which, as shown, intersect the grooves

62 substantially at right angles. The grooves 62 and 64 extend substantially to the inner wall 56 of the die-ring 52 and portions 62a and 64a extend under the die-ring. It will be understood of course that the portions 62a and 64a do not extend as far as the outer wall of the peripheral portion 50, in order to prevent undesired entry of pulp when the die unit is submerged in a pulp slurry. In Fig. 6 a hood 66 is shown, similar to the hood 32 in Fig. 10, and having depending flanges 68 extending into grooves 62, depending flange 70 extending into grooves 64, and having outwardly extending flange 72 frictionally held between the die-ring 54 and the peripheral portion 50 of the die-plate 48.

In Figs. 7 and 8 I have illustrated a highly advantageous embodiment of my invention wherein all of the individual hoods covering minor molding areas, including those adjacent to the die-ring, may be initially positioned or replaced from the face side of the unitary die-plate and wherein every such hood is held in place independently of the die-ring. Thus, in Figs. 7 and 8 there is shown a unitary die-plate 74 having a peripheral portion 76 and a die ring 78 secured by suitable fastening means, such as the screws 80, to said peripheral portion 76. The inner wall 82 of the die-ring 78 defines the substantially parallelogrammatic, specifically rectangular, molding area and the edge of the article to be molded. The die-plate 74 is provided with drainage openings 84 leading therethrough from the molding area. The die-plate is additionally provided with a perimetric groove 86 within the molding area and opening out through the molding area of the die-plate 74 just inside the inner wall 82 of the die-ring. The die-plate 74 is further provided with a set of grooves 88. Grooves 88 are spaced apart and substantially parallel with one another and with the inner walls 82a of the die-ring. The grooves 88 extend substantially to the inner walls 82b of the die-ring and intersect the perimetric groove 86. In a second set, grooves 90 are spaced apart, substantially parallel with each other and with the inner walls 82b of the die-ring. The grooves 90 extend substantially to the inner walls 82a of the die-ring and intersect the perimetric groove 86. The intersecting grooves 88 and 90 all open out through the molding area of the die-plate 74. The grooves 88 are shown as crossing the grooves 90 at substantially right angles thereto, and with the perimetric groove 86, form minor molding areas 92 each of parallelogrammatic, specifically rectangular, shape and each defined by a minor perimetric groove. Each minor perimetric groove is constituted by contiguous portions of the grooves 88 and 90, or 86, 88 and 90, as the case may be.

Each minor molding area 92 has a conformation corresponding to the section of the article to be molded thereon and to this end may be provided with individual forming projections 94, pocket forming cavities 96 and additional and intermediately disposed cavities 98.

There is provided a plurality of wire mesh screen hoods 61, shown in part in Fig. 8, the total of which constitute a screen snugly engaging the die-plate 74 over the entire molding area thereof. Each hood 61 constitutes the foraminous cover for a minor molding area 92. Each hood 61 is shown as being parallelogrammatic, specifically rectangular, in shape and has

marginal flanges 63 extending into the contiguous grooves defining the perimeter of each minor molding area. Each hood 61 may be frictionally locked within its respective minor perimetric groove in any suitable manner. Conveniently and preferably this may be accomplished by means of locking keys or strips 65.

From the construction shown in Figs. 7 and 8 and described hereinabove it will be seen that each of the individual hoods 61 may be initially positioned or replaced from the face side of the unitary die-plate 74 without disturbing the die-ring 78 or removing any of the other hoods 61. Furthermore each hood 61 is held in place independently of the die-ring 78.

A modification of the perimetric groove construction disclosed in Figs. 7 and 8 is shown in Fig. 9. Thus, in Fig. 9 there is shown a die-plate 67 to which is secured a die-ring 69 by suitable fastening means such as the screws 71. A wire mesh screen hood 73 has depending flange 75 which extends into the perimetric groove 77. The inner wall of the perimetric groove 77 is defined by the die-plate 67, and the outer wall of the perimetric groove 77 is defined by the inner wall 79 of the die-ring 71. The depending flange 75 is frictionally locked within the perimetric groove 77 by suitable means such as the locking key or strip 81.

In Fig. 12 I have illustrated in detail a preferred manner of frictionally locking depending flanges of hoods in grooves. Thus in Fig. 12 there is shown a die-plate 83 having drainage openings 85 and grooves 87. Hoods 89 which cover minor holding areas have depending flanges 91 extending into the grooves 87, and stopping short of the bottoms of said grooves. Keys 93 are disposed between depending flanges 91 and serve frictionally to lock said depending flanges in position. The keys 93 are as shown as extending into the bottoms of the grooves 87. In Fig. 13 there is shown, in still further enlargement, a fragment of the die-plate 81 of Fig. 12, depending flanges 91 of hoods 89, and locking key 93.

In Fig. 14 is illustrated an alternative manner of frictionally locking flanges within a groove, wherein the depending flanges 95 of hoods 97 extend into the slot 99 of die 101, and are frictionally locked therein without the aid of additional locking means.

It will be understood that various alternative forms of construction may be employed without departing from the spirit and scope of this invention. Thus the die-ring may be secured to the die-plate in any suitable manner, other than being secured to a peripheral portion of the die-plate as illustrated in the drawings.

It will be further understood that a single hood may be arranged to cover one minor molding area as illustrated herein or may be arranged to cover a plurality of minor molding areas.

It will further be noted that the molding area defined by the die-ring need not be rectangular or parallelogrammatic as illustrated herein, but may be of any suitable closed shape, curved or polygonal, regular or irregular. Sets of grooves may be parallel as shown, or non-parallel, and the grooves may be straight, as shown, or of curved or irregular character. Furthermore the minor molding areas may be of any suitable shape, regular or irregular.

It will further be understood that the conformation of the molding area may be suited to the purpose at hand and may consist of a duplica-

tion of like conformations or may consist of a variety of differing conformations.

Various other modifications in construction and arrangement may obviously be resorted to without departing from the spirit and scope of the invention as defined by the appended claims.

I claim:

1. In an open face pulp molding die-unit for the suction formation of molded pulp egg flats or analogous articles, in combination, a unitary die-plate having a molding area, a die-ring defining the molding area and the edge of the article to be molded, said die-plate being provided with drainage openings leading therethrough from the molding area, said die-plate being further provided with a plurality of retaining grooves opening out into the molding area, extending substantially to the inner wall of said die-ring, and dividing the molding area into a plurality of border sub-areas located adjacent to the die-ring, and, in addition, a plurality of inner sub-areas disposed inwardly of the border sub-areas, each sub-area having a conformation corresponding to the section of the article to be molded thereon, a plurality of wire mesh screen hoods each snugly engaging the die-plate over a sub-area thereof, each hood associated with the inner sub-areas having marginal flanges extending into the contiguous grooves defining the perimeter of the inner sub-area and being frictionally locked within its respective perimetric groove, each hood of the border sub-areas having marginal flanges including flanges which are directly adjacent to the die-ring, such adjacent flanges being frictionally locked to the die-plate, the non-adjacent flanges of such hoods extending into contiguous grooves and being frictionally locked therein, whereby at least those hoods which are associated with the inner sub-areas may be initially positioned or replaced from the face side of the unitary die-plate, and are held in place independently of the die-ring.

2. In an open-face pulp molding die-unit for the suction formation of molded pulp egg flats or analogous articles, in combination, a unitary die-plate having a substantially parallelogrammatic molding area, a die-ring defining the molding area and the edge of the article to be molded, said die-plate being provided with drainage openings leading therethrough from the molding area, said die-plate being further provided with two sets of intersecting grooves opening out into the molding area and extending substantially to the inner wall of said die-ring, the grooves of one set being spaced apart and substantially parallel with one another, the grooves of the other set being spaced apart, substantially parallel with one another, and crossing the grooves of the first set, said grooves dividing the molding area into a plurality of substantially parallelogrammatic border sub-areas located adjacent to the die-ring, and, in addition, a plurality of substantially parallelogrammatic inner sub-areas disposed inwardly of the border sub-areas, each sub-area having a conformation corresponding to the section of the article to be molded thereon, a plurality of wire mesh screen hoods each parallelogrammatic in shape and snugly engaging the die-plate over a sub-area thereof, each hood associated with the inner sub-areas having marginal flanges extending into the contiguous grooves defining the perimeter of the inner sub-area and being frictionally locked within its respective perimetric groove, each hood of the border sub-areas having marginal flanges including flanges which are di-

rectly adjacent to the die-ring, said adjacent flanges being frictionally locked to the die-plate, the non-adjacent flanges of such hoods extending into contiguous grooves and being frictionally locked therein, whereby at least those hoods which are associated with the inner sub-areas may be initially positioned or replaced from the face side of the unitary die-plate, and are held in place independently of the die-ring.

3. In an open-face pulp molding die-unit for the suction formation of molded pulp egg flats or analogous articles, in combination, a unitary die-plate having a molding area, a die-ring secured to the die-plate and defining the molding area and the edge of the article to be molded, said die-plate being provided with drainage openings leading therethrough from the molding area, said die-plate being further provided with a plurality of retaining grooves opening out into the molding area, extending substantially to the inner wall of said die-ring, and dividing the molding area into a plurality of border sub-areas located adjacent to the die-ring, and in addition, a plurality of inner sub-areas disposed inwardly of the border sub-areas, each sub-area having a conformation corresponding to the sections of the article to be molded thereon, a plurality of wire mesh screen hoods each snugly engaging the die-plate over a sub-area thereof, each hood associated with the inner sub-areas having marginal flanges extending into the contiguous grooves defining the perimeter of the inner sub-area and being frictionally locked within its respective perimetric groove, each hood of the border sub-areas having marginal flanges including flanges which are directly adjacent to the die-ring, such adjacent flanges extending between the die-ring and the die-plate and being frictionally locked therebetween, the non-adjacent flanges of such hoods extending into contiguous grooves and being frictionally locked therein, whereby each hood associated with the inner sub-areas may be initially positioned or replaced from the face side of the unitary die-plate, and are held in place independently of the die-ring.

4. An open-faced die assembly for the production from a pulp-water slurry, by suction molding, of egg flats or analogous articles comprising a unitary die plate having a molding area and a peripheral area surrounding the molding area, a die ring superimposed upon the peripheral area, means for securing the die ring to the peripheral area, a die plate carrier, the die plate being provided with drainage openings therethrough leading from the molding area, said die plate being further provided with two sets of retaining grooves opening out into the molding area, the grooves of one set being parallel with one another and with opposing inner sides of the die ring and spaced apart from one another and from said sides of the die ring, and the grooves of the other set being also parallel with one another and the remaining inner sides of the die ring and spaced apart as aforesaid, the grooves of one set crossing at substantially right angles the grooves of the other set, the two sets of grooves dividing the molding area into a plurality of border sub-areas located next adjacent the die ring, and, in addition, a plurality of inner sub-areas disposed inwardly of the border sub-areas, a projection located in each sub-area with a cavity at its upper end, a fine wire mesh hood individual to each sub-molding area and providing the forming surface of the same, the hoods associated with the border sub-areas having marginal portions ex-

tending beneath the contiguous portion of the die ring and removably clamped between the same and the peripheral area of the die plate, and other marginal portions frictionally retained in the grooves defining the border sub-area with which the hood is associated, each of the hoods associated with the inner sub-areas having flanges at their marginal edges retained solely by friction in the grooves defining the sub-area with which the hood is associated, whereby each hood associated with the inner sub-areas may be removed from the front of the die and replacement hoods substituted without disturbing the die ring or removing any of the other hoods associated with either the inner sub-areas or the border sub-areas.

5. In an open-face pulp molding die-unit for the suction formation of molded pulp egg flats or analogous articles, in combination, a unitary die-plate having a molding area, a die-ring disposed adjacent to said die-plate, the inner wall of said die-ring defining the molding area and the edge of the article to be molded, said die-plate being provided with drainage openings leading therethrough from the molding area, said die-plate being additionally provided with a perimetric groove at the margin of the molding area and opening out through the molding area of the die-plate just inside the inner wall of the die-ring, said molding area being divided into a plurality of minor molding areas by spaced grooves opening out through the molding area of the die-plate, each such minor molding area being thus defined by a minor perimetric groove, each said minor molding area having a conformation corresponding to the section of the article to be molded thereon, a plurality of wire mesh screen hoods snugly engaging the die-plate over a minor molding area thereof, each hood having marginal flanges extending into the contiguous grooves defining the perimeter of the minor molding area, each of said hoods being frictionally locked within its respective perimetric groove, whereby each of the individual hoods may be initially positioned or replaced from the face side of the unitary die-plate and is held in place independently of the die-ring.

6. In an open-face pulp molding die-unit for the suction formation of molded pulp egg flats or analogous articles, in combination, a unitary die-plate having a molding area and a peripheral portion surrounding the molding area, a die-ring secured to the peripheral portion of the die-plate, the inner wall of said die-ring defining the molding area and the edge of the article to be molded, said die-plate being provided with drainage openings leading therethrough from the molding area, said die-plate being additionally provided with a perimetric groove within the molding area and opening out through the molding area of the die-plate just inside the inner wall of the die-ring, said die-plate being further provided with spaced grooves opening out through the molding area of the die-plate and intersecting said perimetric groove and forming minor molding areas each defined by a minor perimetric groove, each said minor molding area having a conformation corresponding to the section of the article to be molded thereon, a plurality of wire mesh screen hoods each snugly engaging the die-plate over a minor molding area thereof, each hood having marginal flanges extending into the contiguous grooves defining the perimetric groove

of a minor molding area, each of said hoods being frictionally locked within its respective perimetric groove, whereby each of the individual hoods may be initially positioned or replaced from the face side of the unitary die-plate and is held in place independently of the die-ring.

7. In an open-face pulp molding die-unit for the suction formation of molded pulp egg flats or analogous articles, in combination, a unitary die-plate having a substantially parallelogrammatic molding area and a peripheral portion surrounding the molding area, a die-ring secured to said peripheral portion of the die-plate, the inner wall of said die-ring defining the substantially parallelogrammatic molding area and the edge of the article to be molded, said die-plate being provided with drainage openings leading therethrough from the molding area, said die-plate being additionally provided with a perimetric groove within the molding area and opening out through the molding area of the die-plate just inside the inner wall of the die-ring, said die-plate being further provided with two sets of intersecting grooves, the grooves of one set being spaced apart and substantially parallel with one another, the grooves of the other set being spaced apart substantially parallel with one another and crossing the grooves of the first set to form minor molding areas of parallelogrammatic shape and each defined by a minor perimetric groove, all of said intersecting grooves opening out through the molding area of the die-plate, each said minor molding area having a conformation corresponding to the section of the article to be molded thereon, a plurality of wire mesh screen hoods the total of which constitute a screen snugly engaging the die-plate over the molding area thereof, each hood constituting the foraminous cover for a minor molding area, each hood being parallelogrammatic in shape and having marginal flanges extending into the contiguous grooves defining the perimeter of the minor molding areas, each hood being frictionally locked within its respective minor perimetric groove, whereby each of the individual hoods may be initially positioned or replaced from the face side of the unitary die-plate and is held in place independently of the die-ring.

ERNEST L. SHEPARD.
